ELECTRICAL FILTER

Alexis Badmaleff, Indianapolis, Ind., assignor to
 Radio Corporation of America, a corporation of
 Delaware

Application October 11, 1943, Serial No. 505,800

9 Claims. (Cl. 178—44)

My invention relates to adjustable electrical filters and more particularly to rejection filters used in audio frequency amplifiers and transmission circuits for rejecting some particular frequency or band of frequencies.

An object of my invention is to provide an adjustable filter for rejecting a band of frequencies of desired width with maximum attenuation adjustable at the will of the operator to any frequency within the band.

Another object of my invention is to provide a simplified and inexpensive means for controlling the characteristics of a tuned electrical rejection filter without varying the actual tuning.

The invention will be best understood from the following description when read in the light of the accompanying drawing, in which,

Figure 1 is a schematic diagram of a rejection filter according to the invention.

Figures 2, 3 and 4 are curves showing performance characteristics of the circuit in Figure 1.

Figure 5 is a circuit diagram of a modified form of my invention as applied to radio frequency currents.

When a parallel tuned filter and a series tuned filter are connected in a Wheatstone bridge circuit, as shown in Figure 1, and both are resonant at the same resonance frequency, they act as pure resistances, and form two arms of a Wheatstone bridge. The other two arms are the two resistances R_1 and R_2 , in the form of a potentiometer, R_1 and R_2 varying inversely with adjustment of the potentiometer. When the two resistances R_1 and R_2 are adjusted so that their ratio is the same as the impedances of the two tuned circuits at resonance, the signal will be cancelled out completely, leaving only the harmonics, if any. When the frequency increases or decreases from the resonance point, the impedance of L_1C_1 will decrease, and the impedance L_2C_2 will increase—and since one of the filters will become capacitive and the other inductive, their voltages will be in phase and will add. Since this effect is evident only just before and just after the resonance point (because after that the series filter's impedance is much too large as compared to that of the parallel filter), it will tend to increase the steepness of the slopes of the response curve near the shoulder—and square the shoulder. The general response curve is shown in Figure 2. An input circuit is connected to conjugate points 1 and 2 of the bridge and the output circuit is connected to the other conjugate points 3 and 4 of the bridge.

Referring to Fig. 3, when the parallel filter is tuned to a lower frequency f_1 than f_2 of the series filter, as by adjustable means for the inductors L_1 and L_2 or for the capacitors, then both filters are capacitive between the two resonance frequencies, f_1 and f_2 , and their voltages in this bridge circuit are opposite in phase. These voltages therefore can be made to cancel by adjustment of R_1 and R_2 at any desired frequency f_2 between the two resonant frequencies f_1 and f_2 . The advantages of this, besides the convenient method of frequency rejection adjustment, is that the point of balance at f_3 can be very near the peak of the series filter, effecting a steeper slope and more angular shoulder, as shown in Figure 3.

The input circuit is connected to the end terminals 1 and 2 of the potentiometer R_1R_2 and the output to the slider, or intermediate point, 20 4 and a point 3 between the resonant circuits. The potentiometer comprises two non-resonant impedance elements as two arms of the bridge. Between the resonance points of L_1C_1 and L_2C_2 the system is capacitively reactive, and there is a 25 90° phase shift range included between these points but falling short thereof, as represented by point 8 and 10, Fig. 3. Points 5 and 7 represent two intermediate points of rejection bands selected when the potentiometer is adjusted for 30 balance to other frequencies than f_3 in Fig. 3. Since the resonance points of the two tuned circuits occurs at f_2 and f_1 respectively, the region between those two resonance points is either 35 capacitive or inductive, depending on which is the lower in frequency of the two. Since in the bridge circuit, the phases of the two circuits are in 180° relation, any point can be picked for balance between f_1 and f_2 , by means of adjustment 40 of the amplitude. This adjustment is made by R_1 .

The response curve can be reversed by making the parallel filter L_1C_1 tune to a higher frequency than L_2C_2 ; then both filters become inductively reactive between their two resonant 45 frequencies, as shown in Figure 4.

While the circuit of Figure 1 was used with audio frequency currents, it can also be used, with changed values, for carrier or radio frequency currents. In some cases, however, the resistance 50 potentiometer may be replaced by a capacity potentiometer C_3, C_4 , as shown in Fig. 5, when using radio frequency currents. The filter circuits L_1C_1 and L_2C_2 may be tuned simultaneously by means of ganged adjustable iron cores 12 and 55 14, respectively, to different frequencies, as de-

sired, and the potentiometer will be used to determine the maximum attenuation of the rejection band selected by the adjustment of the cores. The above circuit may be usefully employed in many systems, e. g. in a system of the type shown by Whitelock, 1,925,160, as an improvement.

This rejection filter can be used wherever a single frequency is to be rejected, as for instance 120 cycle hum in amplifier or transmission lines. In that case both tuned circuits are tuned to that frequency. If, however, the frequency to be rejected shifts within two limits, the potentiometer is a convenient means to tune the unwanted frequency out when the two resonant circuits are tuned to the respective two limits.

When used in conjunction with another band pass filter or a high or low pass filter, it is often necessary to reject a frequency very close to the pass frequency. In that case either an inductive or capacitative spread is used, and the balance is attained by the potentiometer, to reject that frequency.

Various circuits and combinations thereof embodying the invention have been disclosed. Numerous changes could be made in the specific circuits by those skilled in the art without departing from the spirit of the invention.

I claim as my invention:

1. In an electrical wave filter, a bridge comprising a parallel resonant circuit in one arm, a series resonant circuit in an adjacent arm, said circuits being tuned to different frequencies, and a potentiometer connected to form the two other arms of said bridge, an input circuit connected to end terminals of said potentiometer and an output circuit connected between a variable intermediate point on said potentiometer and a point between said resonant circuits.

2. In an electrical wave filter, a bridge comprising a parallel resonant circuit as one arm, a series resonant circuit as another arm, said circuits being tuned to relatively different frequencies, a non-resonant impedance element in each of the remaining two arms, said impedance elements being relatively adjustable for varying at will the point of maximum attenuation of the

combined characteristic of said resonant circuits between the resonant points of said circuits.

3. In an electrical wave filter network, a bridge comprising a parallel resonant circuit in one arm tuned to one frequency, series resonant circuit in another arm tuned to a different frequency, a non-resonant impedance device in the other arms of said bridge and being adjustable to vary the ratio of said other arms for varying at will the point of maximum attenuation of the combined characteristic of said resonant circuits between the resonant points of said circuits.

4. The invention as set forth in claim 3 wherein said device is a resistance potentiometer.

5. The invention as set forth in claim 3 wherein said parallel resonant circuit is tuned to a higher frequency than said series resonant circuit whereby the combined characteristic exhibits an inductive reactance characteristic.

6. The invention as set forth in claim 3 wherein said parallel resonant circuit is tuned to a lower frequency than said series resonant circuit, whereby the combined characteristic exhibits a capacitative characteristic.

7. An electrical filter network comprising in combination, an input and an output circuit, a parallel resonant circuit tuned to one frequency, a series resonant circuit tuned to a different frequency, and a potentiometer connected between said resonant circuits, and a connection between a point on said potentiometer and said output circuit for adjusting the maximum attenuation effect of said filter between said frequencies.

8. The invention as set forth in claim 7 wherein means is provided for simultaneously varying the tuning of said resonant circuits.

9. An electrical bridge filter comprising in combination, input and output circuits connected respectively to conjugate points of said bridge, one arm of said bridge including an adjustable resonant circuit tuned to one frequency, another arm of said bridge including an adjustable resonant circuit tuned to a substantially different frequency, the remaining arms including resistors, and structure for varying said resistors in inverse relation.

ALEXIS BADMAIEFF.
